PAPER BOX

Filed Dec. 1, 1927

Inventor:
Harold Raymond Warren
By MacLeod Lahn Lipeland & The
Attorneys.

UNITED STATES PATENT OFFICE.

HAROLD RAYMOND WARREN, OF CAMBRIDGE, MASSACHUSETTS, ASSIGNOR TO P. R. WARREN COMPANY, OF EVERETT, MASSACHUSETTS, A CORPORATION OF MASSACHUSETTS.

PAPER BOX.

Application filed December 1, 1927. Serial No. 237,087.

This invention relates to a new and useful improvement in paper boxes, and has especial reference to that type of box which will serve as a container and also can be effectively used as a display carton. More particularly this invention relates to a box the design of which may be varied to represent a number of objects, but which in this embodiment of the invention is designed in the form of a house.

10 A feature of the invention is the sliding panel in the front of the box simulating a door. Another feature is the display tab insertable through the roof panel of the box 15 and extending thereabove, by means of which the sliding panel may be operated.

The invention will be more fully understood from the following description taken in connection with the accompanying drawings, and the novel features thereof will be 20 pointed out and clearly defined in the claims at the close of the specification.

In the drawings:

Fig. 1 is a plan of a blank formed of a 25 single sheet of paper ready to be folded into a box embodying the invention.

Fig. 2 is a perspective view of the folded box showing the sliding panel in raised position.

30 Fig. 3 is a bottom view of the folded box showing the interengaging flaps by which the bottom may be closed, and

Fig. 4 is a top view, partially cut away of the folded box prior to engaging the roof panel and display tab, showing the top closed by means of interengaging flaps.

Referring now to the drawings, the blank is cut out and creased so as to form the main body portions 1, 2, 3 and 4, said blank being 40 scored or creased, as shown by the dotted lines along the dividing line between said body portions to facilitate the folding.

Said body portions 1, 2, 3 and 4 form the sides and ends of the folded box. Adjacent the ends 3 and 4 on the upper side are the 45 folds 5 and 6, each having a longitudinal slit and being adapted to engage one another, as will be explained hereinafter; and on the lower side the folds 7 and 8. Adjacent the back 2 on the top is the panel 9, having at its free end the extension or sliding panel 10 provided with the tongue members 11 and 12. The purpose of the exten-

sion 10 will be explained hereafter. The panel 9 has a medial slot 13 extending in a direction parallel with the creased edge of the panel. Adjacent the back 2 on the lower side is the flap 14 having slips 15 therein to receive a hook flap. This hook flap 16 having the tongue portion 20 is provided adjacent the lower edge of the front panel 1. On the upper side of the panel 1 is a panel 17 having at its upper extremity a tab 18, which is cut to a width which will permit it to be readily inserted through the slot 13 in panel 9. Panel 1 is provided with a slideway or pair of slots 19 extending vertically part way across its face. Adjacent the outer end edge of the back panel 2 is a glue flap 20 adapted to overlap the free edge of the end 4 and when glued thereto to maintain the box in folded position.

When the box is folded along the creases provided therefor, the folds 7 and 8 are bent upwardly in overlapping position, and are held in place by the interengaging bottom flaps 14 and 16, the tongue portion 20 of fold 16 being inserted in the slits 15 provided therefor in the flap 14. The box is closed at the top by the interengaging flaps 5 and 6, each of which is slit, as shown in the drawings, so that they may be engaged, forming a relatively secure closure. When the box is in folded position, the panel 9, which is of considerably greater width than the box, and the panel 17 extend upwardly at the rear and front edges respectively of the closure. The tab 18 is then inserted through slot 13, and the free edge of panel 9 drawn down so that the tongue members 11 and 12 on extension 10 may be inserted in the slits 19 provided therefor in the front of the panel 1. The completely folded box as shown in Fig. 2 will then be formed.

The roof panel 9 is of sufficient width so that after the door panel 10 has been inserted in the slits 19 provided therefor it will extend well above the top of the closure. If the panel is creased medially along the line of slot 13, the two halves of the panel thus formed will incline upwardly toward the median line in the manner of a roof. Since the panel 10 is slidably mounted in the slideway formed by the slits 19 the roof panel may be collapsed and the tab 18 bent over along its line of union with panel 17 so that the

folded boxes when filled may be shipped in a minimum of space.

It will be obvious that the box may be restored to the desired form simply by pulling the tab 18, thus raising the roof panel 9 to its arched position and causing the panel 10 to move upwardly in the slideway 19, thereby giving the effect of an open door in the front panel.

10 It is to be noted that all of the exposed portions of the container when set up are on the same side of the unfolded blank, so that it is necessary to use a stock coated only on one side of the paper, and that the printing or ornamentation is all placed on the same side. All portions of the other face of the blank will be concealed when the box is set up.

What I claim is:

20 1. A paper box or container made from a single sheet of material, comprising two ends, two sides, a top and a bottom, a panel adjoining the rear side of said box having a slot therein, and having at its outer end a smaller panel, a slideway in the front side of said box, said smaller panel having means for slidably engaging said slideway, and a panel adjoining the front side of said box and having at its outer edge an extension, said extension being cut to a width permitting it to be readily inserted through the said slot in the panel adjoining the rear side.

25 2. A paper box or container in the form of a house, comprising a closure having extending thereabove a panel adjoining the rear side, having a medial slot therein, and having at its outer edge an extension or slide member provided with tongue means, a panel adjoining the front side and having at its outer edge an extension adapted to extend through said slot, and a slideway in the front side comprising a plurality of slits, said tongue means being adapted to slidably engage said slideway.

30 3. A paper box or container in the form of a house, comprising a closure having extending thereabove a panel adjoining the rear side, said panel being of greater width than the box, and having a medial slot extending in a direction parallel with the folded edge of said panel, and having at its free end an extension or slide, a slideway in the face of the front panel, means for slidably engaging said slide in said slideway, and a panel adjoining the top edge of the front side, said last-mentioned panel having a width approximately half that of the panel adjoining the rear side and having a tab extension on its outer end, said extension being adapted to be inserted through the said slot in the said panel adjoining the rear end and to extend thereabove.

35 4. A paper box or container in the form of a house comprising a closure having adjoining its rear side a panel having a medial slot,

and having adjoining its outer edge a small panel having lateral tongue extensions, a panel adjoining the front side having a display member insertable through said slot, said front side having two vertical slits therein adapted to receive said lateral tongue extensions.

5. A display carton comprising two ends, front and rear sides and top and bottom, having adjacent its rear side a panel in the form of a roof extending over the top and having at its front edge a slide, a slideway therefor in the front side of the carton, a panel adjoining the front side of said carton of substantially one half the width of said first panel underlying and forming a support for said panel, both said roof panel and said supporting panel being readily collapsible for shipping by lowering said slide in said slideway.

6. A display carton comprising two ends, front and rear sides and top and bottom, having adjacent its rear side a panel in the form of a roof extending over the top, said panel being creased so that when collapsed the overhanging portion of said panel may be bent downwardly over the front side, and having a slot extending along the line of the peak of the roof, a second panel adjacent the front side of said carton extending under the roof panel and having a tab adapted to be inserted through the slot in the roof panel, a slideway provided in the front side of said carton, a sliding panel carried by said roof panel and having means for engaging said slideway, said tab being adapted to serve as an attaching means for suspending the carton, and being creased at its lower edge so that it may be bent over when the slide is lowered collapsing the roof and support panels transforming the carton into a shipping container occupying a minimum of space.

7. A display carton having two ends, front and rear sides and a top and a bottom, a slideway in said front side, a roof panel adjoining the rear side and having a slide extension slidably engageable in said slideway, a slot extending part way along the ridge of said roof panel, a support panel adjoining the front side of the carton and having a tab insertable through said slot, said tab being adapted to serve as an attaching means for suspending said carton, and for distributing its weight through the body of the box, said tab, support panel, and roof panel all being creased so that they may be readily collapsed permitting the carton to be transformed into a rectangular shipping container.

8. A shipping container comprising a normally rectangular closure having two ends, front and rear sides, a top and a bottom, and having a panel adjoining the rear side extending over the top and bent downwardly part way over the front side, a slideway in said front side, a slide carried by the bent

over portion of said panel slidably mounted in said slideway, said panel having a medial slot extending longitudinally thereacross, a supporting panel adjoining the front side, disposed under said first mentioned panel and means carried by said support member comprising a tab inserted through said slot and normally folded over at its base, which when pulled into upright position will raise the said slide in its slideway causing the first 10 mentioned panel to assume the form of a roof.

In testimony whereof I affix my signature.

HAROLD RAYMOND WARREN.
